US00D617559S

(12) **United States Design Patent**
Chu et al.

(10) **Patent No.:** **US D617,559 S**
(45) **Date of Patent:** **** Jun. 15, 2010**

(54) **HANDLE**

(75) Inventors: **David Ching Chi Chu**, New York, NY (US); **Youjin Nam**, Hoboken, NJ (US)

(73) Assignee: **Tumi, Inc.**, New York, NY (US)

(**) Term: **14 Years**

(21) Appl. No.: **29/327,690**

(22) Filed: **Nov. 11, 2008**

Related U.S. Application Data

(63) Continuation-in-part of application No. 29/320,371, filed on Jun. 25, 2008, now abandoned.

(51) **LOC (9) Cl.** **03-01**

(52) **U.S. Cl.** **D3/318**

(58) **Field of Classification Search** ..... D3/318, D3/279, 282, 324, 276, 289; D8/302, 306, D8/316, 317, 318; 190/18 A, 110, 109, 111, 190/112-115; 16/110.1, 110.3, 114.1, 45
